UNITED STATES PATENT OFFICE.

MAX LAUKE, OF NORTH BERGEN, NEW JERSEY.

AUTOMATIC RECORDING DEVICE.

Application filed November 20, 1920. Serial No. 425,456.

To all whom it may concern:

Be it known that I, MAX LAUKE, a citizen of Germany, and a resident of North Bergen, in the State of New Jersey, have invented 5 certain new and useful Improvements in Automatic Recording Devices, of which the following is a specification.

This invention relates to recording devices and has particular reference to an automatic 10 registering device for recording a number of articles which pass a given point.

The device is primarily intended for use in connection with rails and sliding hangers used in meat markets whereby the number 15 of hangers may be automatically counted.

Another object of the invention is to provide in combination with a rail and a registering mechanism, a means for preventing the choking of the actuating means for the 20 registering mechanism.

A still further object of the invention is to provide a device of the character described which is comparatively simple in construction, inexpensive to manufacture 25 and which is highly efficient in its operation and purpose.

With the above recited and other objects in view some of which will appear hereinafter, the invention resides in the novel construction, combination and arrangement of parts as set forth in the following specification, pointed out in the appended claims and illustrated in the accompanying drawing, in which:

35 Figure 1, is a side elevation of the recording mechanism and register, illustrating the same associated with a rail and movable hangers mounted thereon.

Figure 2 is a similar view illustrating the 40 position of the actuating means in operating position.

Referring to the drawing by characters of reference, 10 designates a suitable support from which is suspended the rail or track 11 45 upon which is mounted a plurality of slideable hangers 12. An electrically operated register 13 is supported from the support 10 and is provided with a pair of spaced contacts 14 connected thereto by the circuit

50 wires 15. A frame comprising the standards 16 connected by a cross bar 17 constitutes a mounting for the vertically movable circuit closer 18 and an actuating arm 19 which is pivoted thereto as at 20. The arm 19 is 55 provided with a groove 21 at its free ex-

tremity which normally receives the track. The arm 19 directly underlies the circuit closer 18 and is adapted to engage and lift the same to effect the bridging of the contacts 14 when the free end of the arm is 60 lifted. By this arrangement, when the shiftable hangers 12 move in the direction indicated by the arrow, the free end of the arm 19 will be lifted to effect the bridging of the contacts 14. In order to provide means for 65 preventing the choking of the actuator arm 19 or the passage of more than one of the hangers simultaneously, use is made of a gravity pawl 22 pivoted as at 23 to the ring 24 supported at its upper end as at 25 from 70 the bar 17. The extremity 26 of the stop pawl overbalances the extremity 27 which is normally engaged by the under side of the actuating arm and received by the notch 28 therein. This construction provides a means 75 for singly permitting the passage of the hangers.

In operation of the device, when the hanger 12 is moved over the track 11, it will lift the free end of the arm thereby raising 80 the circuit closer 18, which in turn will bridge the contacts 14 to operate the register 13. At the same time the extremity 27 of the pawl will be disengaged to permit the heavy extremity 26 thereof to gravitate upon 85 the track 11 to arrest movement of succeeding hangers until the preceding hanger is passed from the extremity of the arm.

While there has been illustrated and described a single and preferred embodiment 90 of the invention it is understood that the same is merely illustrative and that no limitation is necessarily made to the precise structural details only in so far as limited by the appended claims.

What is claimed as new is:

1. The combination with a track having 100 hangers slideable thereover and a register, of means operable by said hangers for actuating the register upon the passage of said hangers past a given point and means operable by said actuating means when in active position to prevent the passage of succeeding hangers.

2. The combination with a track having 105 hangers slideable thereover and a register, of means operable by said hangers for actuating the register upon the passage of said hangers past a given point, comprising an arm pivoted above said track with its free 110

end normally resting on the same, and a vertically movable register actuating member supported in superposed relation to said arm whereby upon lifting of the free end of 5 said arm by the passage of the hangers therebetween, the said member will be raised to actuate the register, and means operable by said actuating means when in active position to prevent the passage of succeeding 10 hangers until the preceding hanger has released the arm, comprising a pawl pivoted between the arm and the track, one extremity of which is weighted to normally gravi-

tate into contact with the track, and the opposite extremity of which coacts with the 15 arm when the free end thereof is supported by the track to maintain the weighted extremity out of contact with the same, whereby upon lifting of the arm, the said weighted extremity will gravitate into engagement 20 with the track for the purpose specified.

Signed at New York, in the county of New York and State of New York, this 16th day of October A. D. 1920.

MAX LAUKE. [L.S.]
